UNITED STATES PATENT OFFICE.

CLAUDIUS SIMON, OF CASCO, WISCONSIN.

STREET-SWEEPER.

1,243,562.

Specification of Letters Patent. Patented Oct. 16, 1917.

Application filed April 10, 1917. Serial No. 161,024.

To all whom it may concern:

Be it known that I, CLAUDIUS SIMON, a citizen of the United States, residing at Casco, in the county of Kewaunee and State 5 of Wisconsin, have invented new and useful Improvements in Street-Sweepers, of which the following is a specification.

This invention relates to street sweepers and it consists in the novel features herein- 10 after described and claimed.

An object of the invention is to improve a street sweeper in point of simplicity, durability and efficiency and particularly to provide new and improved means for elevating the brushes of the sweeper in order that the machine may be readily turned or moved over the surface of a pavement without disconnecting the operating means for the brushes and thus causing unnecessary 20 delay.

The invention also includes other features hereinafter described and more particularly pointed out in the claims.

In the accompanying drawings:—

25 Figure 1 is a side elevation of street sweeper;

Fig. 2 is a top plan view of the same;

Fig. 3 is a longitudinal sectional view of the same;

30 Fig. 4 is a fragmentary sectional view of the same cut on the line 4—4 of Fig. 5;

Fig. 5 is a fragmentary plan view of parts shown in Fig. 4;

Fig. 6 is a transverse sectional view of 35 the same cut on the line 6—6 of Fig. 1;

Fig. 7 is a similar view cut on the line 7—7 of Fig. 1;

Fig. 8 is a transverse fragmentary sectional view of the same cut on the line 8—8 40 of Fig. 1.

The street sweeper comprises a frame 1 of suitable structure which is mounted at its rear portion upon an axle 2, there being wheels 3 journaled for rotation at the ends 45 of the said axle. The forward portion of the frame 1 is supported upon a truck 4 in the usual manner. An operator's seat 5 is mounted upon the forward portion of the frame 1. A hopper 6 is mounted upon the rear portion of the frame 1 and is provided 50 at its rear end with a hinged gate 7.

A shaft 8 is journaled for rotation at the upper portion of the hopper 6 and a sprocket wheel 9 is loosely mounted thereon. A 55 sprocket wheel 10 is attached to one of the wheels 3 and a sprocket chain 11 is trained

around the wheels 9 and 10 and is adapted to transmit rotary movement from one of the wheels 3 to the said sprocket wheel 9. A clutch member 12 is slidably mounted 60 upon the shaft 8 but is restrained to rotate in unison therewith and a spring 13 bears at one end against the clutch member 12 and at its other end against the side of the hopper 6 and is under tension with a tendency 65 to normally hold the clutch member 12 toward the wheel 9 as best shown in Fig. 8 of the drawing. When the clutch member 12 is in engagement with the hub of the wheel 9 the shaft 8 rotates in unison with 70 the wheel 9. Bearings 14 are mounted at the side of the hopper 6 and a rod 15 is journaled in the said bearings. The rod 15 is provided at its upper end with an angularly disposed crank 16 which engages the 75 clutch member 12. The rod 15 is provided at its lower end with an angularly disposed crank 17. A lever 18 is pivoted upon the forward portion of the frame 1 in the vicinity of the operator's seat 5 and any usual 80 or suitable means may be provided for holding the said lever 18 at an adjusted position. A rod 19 operatively connects the lever 18 with the crank 17. Hence it will be seen that when the lever 18 is swung in one direction the rod 19 is moved longitudinally 85 whereby the rod 15 is turned in the bearings 14 and the crank 16 will carry the clutch member 12 out of engagement with the hub of the sprocket wheel 9. When the lever 18 is moved in an opposite direction the said clutch member is moved into engagement with the wheel 9 and is securely held in such engagement under the influence of the spring 13.

A trough 20 is pivotally connected with the upper forward portion of the hopper 6 by means of arms 21 and the said trough is provided at the upper edges of its sides with inturned flanges 22. Bars 23 are pivotally connected with the lower forward end of the trough 21 and are provided with upstanding lugs 24. Bolts 25 are pivotally connected at their rear ends with the lower forward portion of the trough 20 and pass 100 transversely through the lugs 24. Nuts 26 are screw-threaded upon the forward portions of the bolts 25 and coil springs 27 bear at their forward ends against the nuts 26 and at their rear ends against the lugs 24. The springs 27 are under tension with 105 a tendency to normally hold the forward

ends of the bars 23 down, although the said bars may move in an upward direction when they are subjected to sufficient force or pressure to compress the springs 27.

5 A roller 28 is journaled for rotation between the bars 23 at the forward ends thereof and a roller 29 is journaled for rotation at the lower forward portion of the trough 20. Sprocket wheels 30 are mounted upon 10 the shaft 8 and sprocket chains 31 are trained over the sprocket wheels 30 and around the roller 28. The lower runs of the chains 31 are trained under the roller 29. The chains 31 carry brushes 32, the ends of the bodies 15 of which are adapted to move under the flanges 22 hereinafore described and as best illustrated in Fig. 3 of the drawing. A drum 33 is journaled for rotation upon the forward portion of the frame 1 and is 20 provided with ratchet wheels 34. Spring pressed pawls 35 are pivotally mounted upon the frame 1 and engage the ratchet wheels 34 and serve to prevent the drum 33 from rotating in one direction. The shaft 25 of the drum 33 may be provided with a crank handle 36 which may be used for turning the drum 33 in an opposite direction. Cables 37 are arranged to wind upon the drum 33 and the said cables pass over 30 a roller 38 journaled upon the frame 1 and are connected at their rear ends with the lower forward portion of the trough 20. By winding the cables 37 upon the drum 33 the slack may be taken out of the said cables 35 and the lower forward portion of the trough 20 may be supported at a desired elevation 35 with relation to the surface of the street or pavement. Shafts 39 are pivoted upon the frame 1 at points between the drum 33 40 and the roller 38, and the said shafts are provided at one end with angularly disposed hooks 40 which engage over the cables 37. The shafts 39 are provided at their other ends with cranks 41 which are downwardly 45 disposed. A shaft 42 is pivoted upon the frame 1 at a point in advance of the operator's seat 5 and is provided with an up-standing pedal 43. The shaft 42 is provided at its ends with downwardly disposed 50 cranks 44. Rods 45 are connected at their forward ends with the cranks 44 and at their rear ends with the cranks 41.

Thus it will be seen that when the operator places his foot upon the pedal 43 and 55 depresses the same whereby the shaft 42 is turned, the cranks 44 are swung about the axis of the shaft 42 and the rods 45 are moved longitudinally. These in turn, through the cranks 41, swing the shafts 39

whereby the hooks 40 will depress the intermediate portions of the cables 37 and hence the forward portion of the trough 20 may be temporarily raised above its normal position with relation to the surface of the street or roadway.

65 It is of course, understood that when the shaft 42 is manipulated as best described the brushes may remain in movement along the trough 20 and when the forward portion of the said trough is temporarily raised the 70 machine may be turned around or carried over obstructions at the surface of the street or road.

75 From the foregoing description taken in conjunction with the accompanying drawing, it will be seen that a street sweeper of simple and durable structure is provided and that the same may be easily and quickly manipulated to overcome obstructions and to facilitate the turning of the same.

80 Having described the invention what is claimed is:—

1. A street sweeper comprising a frame, a hopper mounted thereon, a trough pivotally connected with the hopper, brushes 85 mounted for movement along the trough, means for moving the brushes, a drum journaled upon the frame, cables arranged to wind upon the drum and connected with the trough, and manually operable means 90 for distorting the cables to raise the forward portion of the trough.

2. A street sweeper comprising a frame, a hopper mounted thereon, a trough pivotally connected with the hopper, brushes 95 mounted for movement along the trough, means for moving the brushes, a drum journaled upon the frame, a roller journaled on the frame, cables arranged to wind upon the drum and trained over the roller 100 and connected with the trough, shafts journaled upon the frame and having hooks which engage over the said cables and manually operable means connected with the shafts and adapted when manipulated to 105 distort the cables whereby the trough is raised.

3. A street sweeper comprising a frame, a trough mounted thereon, bars pivotally connected to the trough, brushes mounted for movement along the trough and the said bars, lugs carried by the bars, bolts pivotally connected with the trough and passing through the lugs and springs carried by the bolts and bearing against said lugs.

110 In testimony whereof I affix my signature.

115 CLAUDIUS SIMON.
